US0D1091084S

(12) **United States Design Patent** (10) **Patent No.:** **US D1,091,084 S**
(45) **Date of Patent:** **** Sep. 2, 2025**

(54) **SHOE**

(71) Applicant: **adidas AG**, Herzogenaurach (DE)

(72) Inventors: **Oddbjørn Stavseng**, Fürth (DE);
Konstantin Baumann, Graben-Neudorf (DE); **Denis Hohmann**, Nuremberg (DE); **Nicholas Galway**, Schwaig (DE); **Adrien Noirhomme**, Nuremberg (DE); **Andreas Schneider**, Nuremberg (DE); **Florian Fick**, Nuremberg (DE); **Faina Chunhan Liang**, Nuremberg (DE); **Jochen Backhaus**, Langenfeld (DE)

(73) Assignee: **adidas AG**, Herzogenaurach (DE)

(**) Term: **15 Years**

(21) Appl. No.: **29/990,066**

(22) Filed: **Feb. 19, 2025**

Related U.S. Application Data

(63) Continuation of application No. 29/922,232, filed on Dec. 21, 2023, now Pat. No. Des. 1,067,595, which is a continuation of application No. 29/822,806, filed on Jan. 12, 2022, now Pat. No. Des. 1,020,192.

(57) **CLAIM**

The ornamental design for a shoe, as shown and described.

DESCRIPTION

FIG. 1 is a perspective view of a shoe.

FIG. 2 is a side view of the shoe of FIG. 1.

FIG. 3 is a side view of the shoe of FIG. 1, from the opposite side as FIG. 2.

FIG. 4 is a front view of the shoe of FIG. 1.

FIG. 5 is a rear view of the shoe of FIG. 1.

FIG. 6 is a top view of the shoe of FIG. 1; and,

FIG. 7 is a bottom view of the shoe of FIG. 1.

The broken lines in the figures denote boundaries and unclaimed structure that form no part of the claimed design.

1 Claim, 4 Drawing Sheets
